UNITED STATES PATENT OFFICE.

JOHN F. TOOHEY, OF TROY, NEW YORK.

DESIGN FOR A GAME-BOARD.

54,877.

Specification for Design.

Patented Apr. 13, 1920.

Application filed September 3, 1919. Serial No. 321,475. Term of patent 7 years.

To all whom it may concern:

Be it known that I, JOHN F. TOOHEY, a citizen of the United States, and a resident of the city of Troy, in the county of Rensselaer and State of New York, have invented a new, original, and ornamental Design for a Game-Board, of which the following is a specification, reference being had to the accompanying drawing, forming part thereof.

The figure is a perspective view of the game board showing my new design.

I claim:

An ornamental design for a game board, as shown.

JOHN F. TOOHEY.
